EDGAR S. SMITH, OF GLENDALE, CALIFORNIA.

AEROPLANE AMUSEMENT APPARATUS.

1,034,654.

Specification of Letters Patent.

Patented Aug. 6, 1912.

Application filed August 21, 1911. Serial No. 645,074.

To all whom it may concern:

Be it known that I, EDGAR S. SMITH, a citizen of the United States, residing at Glendale, in the county of Los Angeles and 5 State of California, have invented new and useful Improvements in Aeroplane Amusement Apparatus, of which the following is a specification.

This invention relates to aeroplane amusement apparatus, the operation of which may be caused to simulate that of aeroplane apparatus freely flown and entirely voluntarily controlled, and wherein or whereupon one or more passengers may be carried in 15 transit within a predetermined or circumscribed course, safely and with a degree of amusement and instruction, one or both.

The invention has for its object the provision of mechanism or apparatus of the character above stated which will be relatively simple and inexpensive in construction and operation, positive and unfailing in operation, and convenient and sure in control, and which will be generally superior in efficiency and serviceability.

With the above and other objects in view the invention consists in the novel and peculiar provision, formation, construction, relative arrangement and combination of 30 parts, members and features, all as herein-after described, shown in the drawing and finally pointed out in claims.

In the drawing: Figure 1 is a top plan view of aeroplane amusement apparatus 35 constructed and organized in accordance with the invention; Fig. 2 is a side elevation of the same, partly in section; Fig. 3 is an enlarged fragmentary view of a feature of the assemblage shown in the other figures; Fig. 4 is a detail vertical transverse sectional view, taken upon the line 4-4, Fig. 1, and looking in the direction of the accompanying arrows, and upon an enlarged scale; and, Fig. 5 is an enlarged fragmentary view of other features of the assemblage shown in the other figures.

Corresponding parts in all the figures are denoted by the same reference characters.

Referring with particularity to the drawing, the aeroplane amusement apparatus therein shown as exemplifying or embodying the invention, in one form of assemblage, comprises an aeroplane A, means B confining the aeroplane to a predetermined or cir-

cumscribed course of travel, means C acting to impart an irregular movement to the aeroplane in its travel, and motive means D for actuating the aeroplane and causing it to move within its circumscribed course of travel.

The aeroplane *a* is shown as of the bi-plane type, having propellers *d* which, within the spirit of the invention, may be actuated to cause the motion of the aeroplane, in substitution for the motive means D. It is to be understood that the aeroplane is provided with the usual steering, guiding and stabilizing means whereby it may be kept or returned to a normal balance condition and presentation of its surfaces to the relatively moving atmosphere. These various means and devices are not illustrated, as they may be of standard well-known construction and function, and are not directly concerned in the invention.

The aeroplane is adjustably mounted upon an arm 6, by connection means *b* which permit the aeroplane to assume different positions, with respect to fore and aft and lateral stability, and presentation of surfaces to the relatively moving atmosphere. The arm 6 is included within the means B confining the aeroplane to a predetermined course of travel. The arm 6 is pivotally and rotatively supported at its inner end portion, opposite to the end at which the aeroplane is connected with said arm, by two bearing members, *c* and *e*, which respectively permit rotation of the arm 6 in a substantially horizontal plane, and oscillation of the same in a vertical plane.

E designates a counterpoise mounted upon the arm 6 with the bearing between the same and the aeroplane; said counterpoise being movably mounted upon the arm 6 and urged toward the bearing members by spring or equivalent tension means *f*.

F designates variable stop means whereby the aeroplane may be temporarily held in varying positions with respect to lateral stability or equilibrium, and which limit lateral instability of the aeroplane.

The connection means *b* comprise a ball and socket or universal joint, the ball member 7 being mounted upon the arm 6, and the socket member 8 being secured beneath the frame of the aeroplane by screws or the like 9, a threaded pin 10 being provided for

locking the socket to the ball to rigidly hold the aeroplane in predetermined position upon the arm 6.

The variable stop means F are arranged at one end of the aeroplane, and comprise a rack 11 mounted upon the arm 6, a spring actuated dog 12 mounted upon the aeroplane, and a cord or the like 13 leading from the dog to the passenger or pilot upon the aeroplane. The top of the rack has a finger 14 directed over the aeroplane, and serving as means limiting the aeroplane to a maximum of lateral stability. The dog 12 co-acts with the teeth of the rack to hold the aeroplane in various positions of lateral instability.

The bearing member c is vertical and rotatable in a sleeve or bushing 15 sunk in a base 16 located in the central portion of the means C for imparting variable movement to the aeroplane. Keyed to the bearing member c is a bevel gear 17 with which meshes a pinion 18 of the shaft of an electric motor 19 illustrated as constituting the motive means D. The upper end of the member c is bifurcated to form a vertical yoke 20 within the arms of which is mounted the bearing member e which is horizontally disposed, and upon which, at either projecting end, outside of the yoke 20, are collars 21, upon the bearing member e; and outside of the same are sleeves 22^a constituting the inner ends of brace arms 22 converging into connection with the arm 6 adjacent to the aeroplane A. Other short braces 23 rise from the arm 6 to the capped ends of the sleeves 21, the arm 6 being thereby suspended at its inner end beneath the bearing member e, to that end extending 40 through the yoke 20.

The means C for imparting irregular movement to the aeroplane comprise a plurality of tracks or ways, 24 and 25, circular in form and concentric with the bearing member c and the gear 17 thereupon. Said tracks or ways are connected at opposed points by switches or cross-overs 26 and 27, whereby a wheel 28 upon the arm 6 may be directed to the track 25 from the track 24 by the switch 27, and to the track 24 from the track 25 by the switch 26. The tracks constitute vertical walls with irregular upper surfaces or edges, formed into alternating and merging elevations and depressions or hills and valleys, with a general curvature in each instance. Preferably the hills of one track or way are arranged in opposition to the valleys of the other track or way. The said tracks or ways are mounted upon a base 29^a central of which is the base 16 of the bearing member c. The wheel 28 is mounted slidably upon a horizontal shaft 29 suspended by a bracket 30 beneath the arm 6 over the tracks or ways 24 and 25, tension means consisting of an ex-

pansive spring or the like 31 being mounted upon the shaft 29 so as to urge the wheel 28 outwardly or toward the outer end of the arm 6.

The operation, method of use and advantages of the improvements in aeroplane amusement apparatus constituting the invention, will be readily understood from the foregoing description, taken in connection with the accompanying drawing and the following statement.

As the motive means D causes the arm 6 to rotate upon its bearing member c, in the direction denoted by the arrow in Fig. 1, the wheel 28 riding over the track or way 24 or 25 of the means C causes the arm 6 of the means B to alternately rise and fall, imparting an irregular movement to the aeroplane at the outer end of the arm 6, simulating the rise and dip of an aeroplane in free flight. It is to be understood that the tracks or ways may be of different conformation to produce different effects in varying the movement of the aeroplane, and the wheel 28 may traverse first one track and then be switched over to the other track by the switch 26 or 27. If the wheel leaves either track or way, by elevation of the arm 6 upon the horizontal bearing member e, due to the lifting force of the re-actions of the relatively moving atmosphere and surfaces of the aeroplane, the spring 31 will cause the wheel to move into position to descend upon the track 25 when the arm 6 descends upon the bearing member e. It will be understood that normally the aeroplane moves in a circular course, being confined to such course by the arm 6, and has its wheel 28 upon one track or way. However, the irregularities of such tracks or ways necessitate the provision of the horizontal bearing member e, which is also utilized in case the arm rises to draw the wheel 28 from either track or way, permitting the aeroplane to fly freely with the exception of limitation to a circular course by the arm 6.

The variable stop means F enable the operator or passenger of the aeroplane to lock the aeroplane in any desired position of disturbed lateral stability, and limit such condition to a maximum tilt or tip laterally. The connection means b permit the aeroplane to tilt laterally and longitudinally, unless the same are locked to prevent such movement by the threaded pin 10. The counterpoise E acts automatically to lessen the pressure of the arm 6 and aeroplane A upon the means C as the speed of rotation increases; thus, at a given speed, causing the arm and the aeroplane to rise free of the means C, more closely simulating flight.

It is to be understood that a plurality of the arms 6, each with an aeroplane and other attendant features and parts may be substituted in installation for the single aeroplane

and attendant features shown in the drawing and above described. The propellers *d* may, as above stated, be positively driven, though not so shown in the drawing, or may 5 be permitted to move in response to the reactions of the air impinging upon them. In dotted lines in Fig. 2 is shown the position of the aeroplane when it rises due to reactions upon its surfaces as above set forth.

10 I do not desire to be understood as limiting myself to the specific provision, formation, construction, combination and relative arrangement of parts, members and features shown and described; but reserve the right 15 to vary the same, in adapting the improvements to varying conditions of use, without departing from the spirit of the invention and the terms of the following claims:

Having thus described my invention I 20 claim and desire to secure by Letters Patent:

1. Apparatus of the character described, comprising an arm rotatively mounted adjacent to one end, an aeroplane mounted upon the other end of the arm, means for 25 rotating the arm, and means for producing oscillations of the arm during the rotation thereof; there being connection means between the aeroplane and the arm permitting free oscillation of the aeroplane relative to 30 a horizontal plane.
2. Apparatus of the character described, comprising an arm rotatively mounted adjacent to one end, an aeroplane mounted upon the other end of the arm, means for 35 rotating the arm, and means for producing oscillations of the arm during the rotation thereof; there being connection means between the aeroplane and the arm permitting free oscillation of the aeroplane relative to 40 the arm; and stop means limiting such latter oscillation.
3. Apparatus of the character described, comprising an arm rotatively mounted adjacent to one end, an aeroplane mounted 45 upon the other end of the arm, means for

rotating the arm, and means for producing oscillations of the arm during the rotation thereof; there being connection means between the aeroplane and the arm permitting oscillation of the aeroplane relative to the 50 arm; and stop means variably limiting such latter oscillation.

4. Apparatus of the character described, comprising an arm mounted for movement in a circular path and for oscillation, an 55 aeroplane mounted upon the arm, motive means for the arm, and means co-acting with the arm to cause such oscillation; said last named means comprising a plurality of curved irregular surfaced concentric structures beneath the arm, and an adjustable wheel upon the arm for co-action with said 60 concentric structures.

5. Apparatus of the character described, comprising an arm mounted for movement 65 in a predetermined path, motive means for the arm, an aeroplane mounted upon the arm, means for causing oscillation of the arm during its normal movement, and an adjustable automatically operating counter- 70 poise for the arm.

6. Apparatus of the character described, comprising an arm mounted for movement in a circular path, an aeroplane mounted upon the arm, motive means for the arm, 75 and means co-acting with the arm to cause oscillation of the same; said last named comprising a plurality of curved irregular means comprising a plurality of curved irregular surfaced concentric tracks beneath 80 and coacting with the arm and connected by a switch.

In testimony whereof, I have signed my name to this specification in the presence of two subscribing witnesses.

EDGAR S. SMITH.
